(57) CLAIM

The ornamental design for a dispensing closure with hinged lid, as shown and described.

DESCRIPTION

FIG. 1 is a front view of a dispensing closure with hinged lid, said lid being in a closed position, showing our new design;

FIG. 2 is a back view thereof;

FIG. 3 is a left side view thereof;

FIG. 4 is a right side view thereof;

FIG. 5 is a top plan view thereof;

FIG. 6 is a bottom view thereof; and

FIG. 7 is a front perspective view thereof.

FIG. 8 is a front view of a dispensing closure with hinged lid, said lid being in an open position, showing our new design;

FIG. 9 is a top plan view thereof;

FIG. 10 is a left side view thereof; and,

FIG. 11 is a bottom view thereof.
